(57) **CLAIM**

The ornamental design for a portion of a disc brake lever, as shown and described.

DESCRIPTION

FIG. 1 is a perspective view of a portion of a disc brake lever in accordance with my new design;

FIG. 2 is a front elevational view thereof;

FIG. 3 is a rear elevational view thereof;

FIG. 4 is an end elevational view thereof;

FIG. 5 is an opposite end elevational view thereof;

FIG. 6 is a top plan view thereof;

FIG. 7 is a bottom plan view thereof;

FIG. 8 is a rear elevational view of a portion of a disc brake lever showing a second embodiment of my new design, the appearance of the front view is the same as in FIG. 2;

FIG. 9 is an end elevational view of FIG. 8;

FIG. 10 is an opposite end elevational view of FIG. 8;

FIG. 11 is a top plan view of FIG. 8; and,

FIG. 12 is a bottom plan view of FIG. 8.

The lever portions shown in broken lines throughout the drawing views are for illustrative purposes only and form no part of the claimed design.
